Thomas H. Wood, of Utica, N. Y. and
Henry S. Hubbell & Alfred S. Hubbell, of Buffalo, N. Y.
Letters Patent No 1574, dated Jan. 7, 1862.

The schedule referred to in these Letters Patent and making part of the same.

To all whom it may concern:

Be it known that we, Thomas H. Wood, of the City of Utica, and County of Oneida, State of New York, and Henry S. Hubbell and Alfred S. Hubbell, of the City of Buffalo, County of Erie and State aforesaid, have invented or produced a new and original design for a cooking stove, called the Relief, and we do hereby declare that the following is a full and exact description of the same, reference being had to the accompanying photograph and the letters of reference marked thereon.

Letter A, the top plate. B.B. the side and side over door. The other side and door being like them, C.C. the upper front of stove. D.D.

the lower front of stove. E.F. the front doors. G. the middle bottom or Hearth of stove.

What we claim as our invention or production and desire to secure by Letters Patent, is the general design and configuration represented in the accompanying photograph.
